[57] CLAIM

The ornamental design for a flower pot, as shown and described.

DESCRIPTION

FIG. 1 is a front perspective view of a flower pot showing my new design;

FIG. 2 is a front perspective view of a second embodiment similar to FIG. 1, the only difference being surface texture;

FIG. 3 is a top plan view of the flower pot of FIG. 1;

FIG. 4 is a front elevational view of the flower pot of FIG. 1, a view taken from the rear being a mirror image thereof;

FIG. 5 is a left side view of the flower pot of FIG. 1, a view taken from the right side being a mirror image thereof;

FIG. 6 is a front perspective view of a third embodiment of a flower pot showing my new design; and,

FIG. 7 is a front perspective view of a fourth embodiment of a flower pot similar to FIG. 6, the only difference being the surface texture;

FIG. 8 is a top plan view of the flower pot shown in FIG. 6;

FIG. 9 is a front elevational view of the flower pot of FIG. 6, a rear elevational view being a mirror image thereof; and,

FIG. 10 is a left side view of the flower pot of FIG. 6, the right side view being a mirror image thereof.
